UNITED STATES PATENT OFFICE.

GEORGE J. AIGNER, OF CHICAGO, ILLINOIS.

INDEX-TAB.

1,347,241.

Specification of Letters Patent.

Patented July 26, 1920.

Original application filed May 14, 1917, Serial No. 168,447. Divided and this application filed July 5, 1917. Serial No. 178,830.

To all whom it may concern:

Be it known that I, GEORGE J. AIGNER, a citizen of the United States of America, residing at Chicago, in the county of Cook and State of Illinois, have invented new and useful Index-Tabs, of which the following is a specification, reference being had to the accompanying drawings, illustrating same.

My invention relates to indexes, for use in connection with books, various kinds of letter and card files, loose leaf arrangements, etc. It may, however, be used in various places and adapted for various conditions.

This application is a division of my co-pending United States patent application Serial No. 168,447, filed May 14, 1917, on index tabs.

One object of my present invention is to provide improved index tabs as herein set forth.

Another object of my present invention is to provide improved strips of index tabs as herein set forth, constructed so that the single or individual tabs of the strip may be readily and quickly detached therefrom for use.

Other objects will be apparent from the following specification.

In the accompanying drawings illustrating some of the preferred forms of my invention, Figure 1 is a side elevation of a strip of index tabs of the invention, with portions cut away to show the interior construction of the strip; Fig. 2 is a top end view of the strip of tabs of Fig. 1; Fig. 3 is a side elevation of a single tab taken from a strip of tabs similar to the strip shown in Fig. 1; Fig. 4 is a side elevation of a strip of another form of index tabs of this invention, with portions cut away to show the interior construction of the strip; Fig. 5 is a top end view of the strip of tabs of Fig. 4, showing the attachable ends of the tabs spread apart for moistening, to condition them to be glued to their proper sheets for use; and Fig. 6 is a side elevation of a single tab taken from a strip of tabs similar to the strip shown in Fig. 4.

Like characters refer to like parts in the several figures.

Index tabs in strip form have generally been made with the series of tabs in the form of a continuous strip having no incisions between the various characters on the strip to enable the individual tabs to be readily detached from the strip for use. In

other forms of tabs the individual tabs of a set are cut entirely apart from each other and placed loosely in a box. In the former class of tabs it is necessary to cut the individual tabs from the strip for use, entirely across the strip, but in such a strip of tabs the cutting cannot be uniformly done by hand so that the individual tabs after being cut apart will have a uniform appearance, width, etc.; and in the latter class of tabs it is necessary to sort out the individual tabs of a set of different characters and arrange them in their proper order before gluing them to their respective sheets for use, which consumes considerable time and is a great bother.

In my present invention I have devised an improved tab and strip of tabs which eliminate all of the objectionable features above mentioned. I accomplish this result by cutting the individual tabs A, B, C, D, E, etc., of a strip of tabs, nearly apart from each other, as shown by lines 1 1 which represent cuts in the strips of tabs, but still leave the individual tabs of a strip all connected together by narrow attachment portions 2 2, preferably as shown. These attachment portions 2 2, in the forms of my invention illustrated in the accompanying drawings, are at the extreme front edge of the strip. With this construction the attachment portions in the folded edge of the strip and in a portion of the filler hold the strip of tabs stiffer and straighter than where the attachments are at other portions of the strip, due to the stiffness of the filler and the folded edge portion. With the attachments at the front folded edge of the strip it is easier to clip the individual tabs apart, because it is easier to clip one portion than two portions which are separated from each other as in the opposite legs of the tabs, especially with tabs having angularly projecting legs as illustrated in Fig. 4. It is hard to clip the last-mentioned tabs apart if the attachment portions 2 2 are medially disposed in the strip between the attachment legs of the tabs. Clipping the tabs apart gives smoother, more uniform and better appearing edges than twisting the tabs apart.

With the cuts 1 1 between the individual tabs of a strip, providing the small attachments 2 2 between the tabs, the tabs of a set or series are kept in their proper order, thus eliminating the objectionable feature of having to sort them out where they are cut clear

apart from each other as above stated. My improved tabs may, however, be readily and quickly separated from each other for use, preferably by clipping the small attachments therebetween, the cuts 1 1, serving as guides to enable the attachments 2 2 to be uniformly clipped so that the tabs present a uniform appearance after being clipped apart. Thus, the cuts 1 1 eliminate the necessity of having to cut the individual tabs apart from each other entirely across the strip as in the tabs above mentioned, which cutting cannot be done by hand so that the severed tabs have a uniform width and appearance.

In all of the tabs illustrated, each tab comprises an outside portion 3, which may be of leather, celluloid, paper, canvas, cloth, etc., and the inner portion or filler 4 for stiffening the front portion of the tab, the outside portion 3 being folded over around the inside portion 4, preferably as shown in Figs. 2 and 5, and being suitably glued or cemented thereto so that the portions 2, 4, 3 25 constitute a solid body portion. The filler 4 is preferably cemented in place in the long folded portion 3 in the form of a long strip, before the cuts 1 1 between the individual tabs are made. The filler 4 may be of paper, 30 canvas, leather, cloth, or any other suitable material, and I preferably make the filler 4 the same color as the outside portion 3 of the tabs, so as to present a better appearance along the top and bottom edges of the tabs. 35 The inner surfaces 5 5 of the attachable legs 6 6 of the tabs, back of the filler strip 4, are preferably gummed, so that they may be moistened and glued to their proper sheets very readily. In moistening the surfaces 5 5 of the tabs, the legs 6 6 thereof may be spread apart as shown in Fig. 5 and pressed or rubbed against any suitable moist sponge or other object.

The attachment portions 2 2 between the individual tabs of a strip are preferably located as shown in the drawings, so that each attachment comprises part of the folded portion 3 and filler 4.

Each of the individual tabs shown in Fig. 4 is constructed as shown in Fig. 6, that is, with one of the attachable legs 6 extending upwardly from the body portion of the tab and the other attachable leg 6 extending downwardly from the body portion of the tab, preferably as shown. This construction is provided so as to reinforce the sheet to which the tab is attached for use, adjacent to the tab, and thus prevent the sheet from tearing in case the tab is twisted or roughly handled in turning the sheet. This construction greatly lengthens the life of usage of the sheets and tabs. I wish it to be understood that I may vary the shape of the legs 6 6 of the tab of Fig. 6 as desired.

In certain forms of my tabs I may do 65 away with the filler 4 and glue the portions 3 3 of the fold directly to each other, thus providing a stiff solid portion for the front portion of the tabs.

The characters on a set of tabs may be 70 the letters of the alphabet, the numerals, the days of the month, abbreviations for the months, abbreviations for States, names of individuals, companies, etc., or, in fact, anything desired.

I do not wish to limit this invention to all of the particular details herein set forth, as various modifications thereof may be made or utilized without departing from the scope of the appended claims.

The broad idea of connecting the individual tabs of a strip by small severable attachments, is claimed in my United States Reissue Patent No. 14,550, on index tabs, re-issued Nov. 19, 1918.

What I claim as my invention is:

1. A series of index tabs arranged in the form of a strip according to a predetermined arrangement, each of the tabs having a horizontal body portion composed of a folded 90 portion, and attachment legs for each of the tabs projecting angularly from the rear end of the horizontal body portion, one upwardly and one downwardly when the tab is attached to a vertically-disposed sheet, the consecutive tabs of the strip being connected together only by narrow severable attachments at the extreme front edge of the strip holding the tabs in their predetermined arrangement in the strip but permitting of 100 them being readily detached from each other for use.

2. A set of index tabs of the character set forth comprising a series of tabs normally in a strip and provided with different characters thereon arranged consecutively according to a predetermined arrangement, the said strip comprising a folded portion having a front portion for the characters and a rear portion for providing attachment 110 legs for the individual tabs, the said tabs being cut entirely apart through the said rear portion and through the said front portion to within a short distance from the front edge of the strip whereby narrow severable attachments between the individual tabs are provided at the front edge only of the strip, the said attachments holding the said tabs in their predetermined arrangement in the strip but permitting of them being readily 120 detached from each other for use.

As inventor of the foregoing I hereunto subscribe my name at Chicago, Illinois, this 28th day of June, 1917.

GEORGE J. AIGNER.
